United States Patent Office

Des. 189,162
Patented Nov. 1, 1960

189,162

TELEVISION RECEIVER

Cyrilla A. Seymour, Chicago, Ill., assignor to Admiral Corporation, Chicago, Ill., a corporation of Delaware

Filed Nov. 20, 1959, Ser. No. 58,419

Term of patent 3½ years

(Cl. D56—4)

Fig. 1.

Fig. 2.

Fig. 3.

The dominant features of my design reside in the portions shown in full lines in the drawing.

I claim:

The ornamental design for a television receiver, substantially as shown and described.
